UNITED STATES PATENT OFFICE.

BERT E. RICO, OF LOS ANGELES, CALIFORNIA.

HOSE-STAND.

1,306,676.

Specification of Letters Patent. Patented June 10, 1919.

Application filed August 28, 1918. Serial No. 251,444.

To all whom it may concern:

Be it known that I, BERT E. RICO, a citizen of the United States, and a resident of Los Angeles, in the county of Los Angeles,

5 State of California, have invented certain new and useful Improvements in Hose-Stands, of which the following is a specification.

My invention relates primarily to a stand 10 for garden hose or the like and it has for its object to provide a stand for holding the nozzle in the desired positions while sprinkling water in irrigating and the like.

Another object is to provide a stand 15 which will be cheap, simple in construction and operation and which will hold the nozzle in a number of different positions without alterations.

A still further object is to provide a device 20 of the above character which will hold the nozzle without being fastened in the ground.

Other objects and advantages will appear hereinafter and while I have shown and will 25 describe my preferred form of my invention it will be understood that I do not limit myself to such preferred form but that various changes and adaptations may be made therein without departing from the spirit 30 of my invention.

In the drawings accompanying and forming a part of this application:

Figure 1, is a side elevation of my holder.

Fig. 2, is a top plan of Fig. 1.

35 Figs. 3, 4, and 5 are views showing different applications of my stand in positions of use.

Referring to the drawings my device comprises a single piece of wire or the like bent 40 centrally of its length into one or more convolutions 6 and then having an oppositely disposed loop or semicircle 7 bent in each of its legs immediately below said convolutions, the wire at the termination of these 45 loops being then crossed in a parallel plane and the legs 8 and 9 being then bent to extend at an angle rearwardly and downwardly. Pivotaly mounted on one of the legs 8 is a swinging cross bar 10 which bar 50 has formed centrally of its length an upwardly curved loop 11, opening down-

wardly. Bar 10 extends across the space between the legs and its free end is adapted to bear against the other leg 9 to retain the nozzle in its position of use.

55

In the use of my stand the end of the hose is first positioned within the loop 11. The legs of the stand are then forced together which forced the loops 7 away from each other thereby enlarging the opening therebetween so that the end of the nozzle may be passed into said opening. The legs are then released and the resiliency of the convolutions 6 forces the same apart thereby causing the loops 7 to move toward each 60 other and grip the nozzle between them thereby securely retaining said nozzle in position for use.

65

The operation of the stand as illustrated in Figs. 5 and 6, will be obvious from the 70 above and it will also be obvious that various other applications of my stand may be made without altering the device.

Having described my invention what I 75 claim is:

1. A stand for hose formed from a single piece of wire bent centrally of its length to form a plurality of convolutions and having its legs extending downwardly and being provided with oppositely disposed loops at 80 the termination of said convolutions, said legs being crossed at the termination of said loops and then being bent at an obtuse angle; and a cross bar pivotally mounted on said obtuse angled legs provided centrally 85 of its length with a downwardly opening loop, the free end of said bar being adapted to rest upon the upper face of the other leg.

85

2. A hose stand formed from a single piece of wire bent centrally of its length to 90 form a convolution and having its legs at the termination of said convolution bent to form oppositely disposed loops and then crossed and then bent to extend at an obtuse angle; and a cross bar pivotally mounted 95 at one end on one of said obtuse angled legs and being provided centrally of its length with a downwardly depending loop, the free end of said bar being adapted to rest upon the other of said legs.

BERT E. RICO.
